UNITED STATES PATENT OFFICE.

JUDSON HAYWARD, OF NEW YORK, N. Y.

HOISTING DEVICE.

SPECIFICATION forming part of Letters Patent No. 744,071, dated November 17, 1903.

Application filed March 19, 1903. Serial No. 148,545. (No model.)

To all whom it may concern:

Be it known that I, JUDSON HAYWARD, a citizen of the United States, and a resident of the city of New York, borough of Manhattan, in the county and State of New York, have invented certain new and useful Improvements in Hoisting Devices, of which the following is a specification.

My invention relates to improvements in hoisting devices, and particularly to means by which the horizontal swinging of a boom is effected and controlled.

My invention will be hereinafter defined in the claims.

15 I have shown a preferred embodiment of my invention in the drawings accompanying herewith, in which—

Figure 1 is a plan view with certain parts removed and in section. Fig. 2 is a side elevation, and Fig. 3 is a diagram showing in front elevation the manner of arranging and leading the rope by which the boom is held.

20 My invention is applicable to booms of any type, but is more particularly designed for use with booms of that type known as "automatic swinging" booms. Such booms are provided with pivots so inclined that the boom tends to swing to a central position from a point on either side thereof. With these 25 booms is employed a two-rope hoisting system, one rope being on each side of the boom, said ropes passing through guides somewhat removed from the foot of the boom, so that if one rope be strained more than the other the 30 boom will tend to swing to that side.

35 In the accompanying drawings, A represents a derrick-frame; B, a boom pivoted thereto at C in the manner described; F and F', the two hoisting-ropes; G and G', the 40 drums which operate said ropes, and H H' the guides for said ropes, said guides being located laterally removed from the boom either at the level of the foot of the boom, as shown, or at any other desired level. The above 45 mechanism is common to the ordinary automatic swinging booms. It has been found that with a boom so equipped it is not always possible to control it in the manner desired. For instance, when such a boom is used with 50 a clam-shell or equivalent type of automatic bucket using an opening and closing rope it

can be made to dig only in the central position; also, when the bucket is dumped at one side of the center the strain of the holding or hoisting rope when closing-rope is released 55 assists the tendency to swing back to the center before the bucket has discharged its load, and consequently the boom swings back with a rush which carries it beyond the center, and thus time is lost. Under the same conditions 60 when the strain is thrown upon the holding-rope the boom commences to swing back before the bucket is properly placed to dig. To remove these objections and to improve 65 the operation of the device, I have added my novel features.

To the boom at a point sufficiently removed from its lower pivoted end is secured the ends of holding-ropes E. Means are provided for taking in and paying out these ropes as the 70 boom swings and also for holding said ropes, as well as for taking up slack, so that the controlling action upon the boom is instant. In the means herein shown the holding-rope E is substantially endless, and the means 75 for taking up and paying out the ropes consist of the drums D and D'. These drums constitute a convenient means for taking up and paying out the ropes and, together with the brakes, for holding them; but it is evident 80 that other means may be employed for securing the same results. It is also evident that instead of a single rope, as shown, three ropes may be used, two leading from the boom each to its respective drum and a third 85 forming a loop between the two drums. Each side of the rope leads from the boom to and over a guide-pulley I', carried by the derrick-frame at a point laterally removed from the boom, so that by holding one or the other of 90 these ropes the boom may be prevented from swinging in either direction. The ends of this rope are then carried each about its respective drum D or D' a sufficient number of times to secure a good frictional grip thereon. If desired, the rope may be clamped or otherwise secured to the drum. The rope preferably passes over guide-pulleys I, intermediate the pulleys I' and the drums. Between the two drums is what may be called 95 a "compensating rotative connection," by which term I mean a connection whereby as

each drum is turned to pay out rope it tends to turn the other so as to take in its rope and yet a connection of such a yielding or flexible character that compensation is made 5 for variation in amount of rope required. In other words, the rotative connection is of such nature that there may be a variation in the rates of the two drums without affecting the rotative effect. The means herein shown for 10 accomplishing this result consists of the elevated pulleys L L^2 , over which the rope between the drums passes, and the tension-weight W , which is suspended from a pulley L' , carried by a loop of the rope extending between 15 the pulleys L and L^2 . This device causes each drum to tend to turn the other, and yet permits variations in their rates of turning. The weight acts both as a take-up and a tension for the ropes. The means herein shown for holding 20 the rope consists of a band-brake J upon each drum, said brakes being controlled by levers k' through rods k and the brake-lever K . Any other means for holding the ropes which will permit the free running thereof when desired may be used. The amount of rope extending from the boom to both guide-pulleys I' is not the same for all positions of the boom; but the take-up device (most clearly shown 25 in Fig. 3) compensates for this and keeps the rope at all times taut, so that when the brake is applied its restraining action is immediately felt upon the boom. Without such a device there would be a certain amount of slack to take up, which process would result 30 in a shock when the rope became taut, and this would strain the parts, as well as interfere with certain and exact handling of the load. With a device such as herein described no trouble of this sort occurs. The brakes 35 may be applied to the drums separately, but preferably both together. As the slack-taking weight is between the drums or the means by which the rope is held, it does not have to resist any of the pull of the boom, but need 40 only be sufficient to take up slack and the friction of the drum and guide-pulleys. By these means the boom may be securely held in any position, irrespective of how the main ropes F F' are operated. The drums D D' 45 need not be connected in any way with a motor or driving mechanism, as it is not necessary that they should communicate any power to the rope, but only hold it. They may be placed wherever most convenient. 50

55 It is evident that my invention may be embodied in other forms than that herein shown. I do not, therefore, desire to be limited to this particular form of device.

Having thus described my invention, what I 60 claim, and desire to secure by Letters Patent, is—

1. In combination a boom, holding-ropes secured to said boom and extending to either side thereof, a drum receiving each holding- 65 rope, a brake for each drum, and a compensating rotative connection between the drums.

2. In combination, a swinging boom, a holding-rope having its ends secured to the boom, guides for said rope laterally removed from the boom, independent means for holding 70 each branch of said rope, and a take-up and tension device acting upon said rope between said holding means.

3. In combination, a swinging boom, a holding-rope having its ends secured to the boom 75 and extending laterally to either side, independent means for holding each branch of said rope, and a running take-up and tension device acting upon said rope between the holding devices.

4. In combination, a swinging boom, a holding-rope having its ends secured to the boom, guides for said rope located to either side of the boom, two drums about each, of which one branch of the rope passes, brakes on said 85 drums, a loop in said rope between the drums, and a weight suspended in said loop.

5. In combination, a swinging boom, holding-ropes adapted to control the swinging of said boom, independent means for holding 90 each of the holding-ropes, and a take-up and tension device acting upon said ropes between the said holding means.

6. In combination, a swinging boom, holding-ropes adapted to control the swinging of 95 said boom, independent holding means acting upon each holding-rope, and a compensating tension and take-up device acting upon the ropes between said holding means.

7. In combination, a swinging boom, a holding-rope having its ends secured to the boom from opposite sides and adapted to control the swinging of said boom, independent holding devices for each branch of the rope, and a tension and take-up device having a running engagement with the central portion of 100 the rope between the holding devices.

8. In a hoisting device in combination, a boom, two hoisting-ropes, guides for said ropes removed from the boom at either side 110 thereof, means for operating said ropes independently, controlling-ropes connected with said boom and extending to either side thereof, guides for the controlling-ropes removed laterally from the boom, means for holding 115 upon said controlling-ropes and means for automatically keeping said ropes taut.

9. In a hoisting device in combination, a boom, two hoisting-ropes, guides for said ropes removed from the boom at either side 120 thereof, means for operating said ropes independently, controlling-ropes connected with said boom and extending to either side thereof, guides for the controlling-ropes removed laterally from the boom, two drums adapted 125 each to receive one of said ropes, brakes for said drums and a compensating rotative connection between said drums.

10. In a hoisting device in combination, a boom, two hoisting-ropes, guides for said 130 ropes removed from the boom at either side thereof, means for operating said ropes inde-

pendently, controlling-ropes connected with
said boom and extending to either side there-
of, guides for the controlling-ropes removed
laterally from the boom, two drums each re-
5 ceiving one of said ropes, brakes for said
drums, a rope winding upon both drums and
having a loop between the drums and a weight
suspended in said loop.

In testimony whereof I have hereunto af-
fixed my signature, this 16th day of March, 1903,
1903, in the presence of two witnesses.

JUDSON HAYWARD.
